UNITED STATES PATENT OFFICE.

WILLIAM J. STEVENS, OF NEW YORK, N. Y.

JOINT FOR RAILWAY-RAILS.

SPECIFICATION forming part of Letters Patent No. 288,378, dated November 13, 1883.

Application filed August 26, 1882. (No model.)

To all whom it may concern:

Be it known that I, WILLIAM J. STEVENS, of the city and county of New York, in the State of New York, have invented a new and 5 useful Improvement in Joints for Railway-Rails, of which the following is a specification.

The object of my invention is to provide a very secure and yet simple joint for the meeting ends of railway-rails; and my invention 10 consists in what I term a "combined fish-plate joint and chair," which is composed of a base-plate having an entirely flat upper surface, and extending horizontally beyond the bases of the rails, at each side thereof, and fish-plates pro- 15 vided with horizontally-extending flanges, which rest on and are secured by bolts or rivets to the portions of the flat surface of the base-plate beyond the bases of the rails.

The invention also consists in a fish-plate 20 having its outer side of novel shape, whereby it is made to serve the purpose of a nut-lock, to preclude the nuts of the fish-bolts from becoming loosened, or to so retard their unscrewing as to prevent their becoming loosened by 25 any jar.

In the accompanying drawings, Figure 1 represents a side elevation of my improved joint. Fig. 2 represents a transverse section thereof, and Fig. 3 represents a transverse section 30 of the joint before the fish-bolts are applied.

Similar letters of reference designate corresponding parts in all the figures.

The rails A, which are to be joined, are of the usual form. The joint is composed of three 35 principal parts—a base-plate, B, and two fish-plates, C—and the base-plate is intended to be of the same or nearly the same length as the fish-plates. The three parts of the joint may 40 be composed of iron or steel, and are rolled to give them the desired form. The base-plates B may be rolled separately, or they may be formed by cutting bar or plate iron to the desired length.

45 The base-plate B has a flat upper surface, on which the bases a of the rails rest, and the fish-plates C have flanges C', which extend laterally over and approximately fit the bases of the rails. The flanges C' project beyond the edges 50 of the bases a and rest upon the base-plate B,

on the same level as the bases of the rails, and are represented as secured to the base-plate by rivets b; or one of them may be bolted, if desired.

The fish-plates C, when rolled, are preferably 55 of such form that when their flanges C' are secured to the base-plate their upright portions will flare slightly away from the web c of the rail, as shown in Fig. 3, so as to enable the rail to be slipped in endwise between the fish- 60 plates, or to enable the chair or fish-plate to be slipped upon the rails longitudinally thereof. The fish-bolts are then inserted, and both fish-plates are drawn tightly in against the opposite sides of the web c, as shown in Fig. 2. 65 The flanges of the fish-plates are made thinner than the main portions thereof, so that they will spring and allow the fish-bolts to draw the plates against the webs of the rails. The fish-plates C hold the ends of the rails in coincidence, and, in connection with the base-plate 70 B, a chair is formed, which holds the rails in a very secure manner, and which may be termed "continuous," because the base-plate is as long or nearly as long as the fish-plates. 75

The outer face of each fish-plate C, around the holes through which the fish-bolts D pass, is perpendicular to the axes of said holes, so that the nuts will be afforded an even bearing on the fish-plate and the bending of the bolts 80 prevented when the nuts are screwed up tightly. Beyond such perpendicular portion and near the upper edge of the fish-plate is a slight incline, d, which is at such a distance from the holes through which the fish-bolts D are inserted that the corners of the nuts e will strike the incline, while when the nuts are turned to the position shown in Fig. 1 they will clear the incline. The inclines come within the range of the corners of the nuts e, and as the 85 latter are screwed up their corners bear against the incline d, and although the incline does not offer enough resistance to prevent the nut from being turned with a wrench, it does offer a sufficient resistance to prevent the unscrewing of the nut by any jar, and therefore serves to lock the nuts very effectually.

95 Of course the incline on the fish-plate, against which the heads of the bolts D bear, is of no use; but the incline adds nothing to their 100

cost, and all the fish-plates are rolled with it, so that the bolts may be inserted from either side for the right and left hand rails.

In some cases it might be desirable to secure 5 one fish-plate to the base-plate B by bolts, instead of rivets *b*, so that when that fish-plate is removed the chair can be applied laterally to the rails, and in such case the incline *f* on the flange C' of the fish-plate would prevent 10 the unscrewing of the nuts of said bolts.

My improved joint is advantageous for many 15 reasons. The base-plates and fish-plates are of simple form, and can all be produced cheaply by rolling. They have but few angles, and therefore are not liable to have flaws and to 20 crack or split when strained. The base-plates have a very broad and extensive bearing on the ties, and the weight is distributed over a large area. The base-plates are flat on the 25 under sides, and will rest squarely on the ties without notching and weakening the latter. I am not aware that these advantages have all been possessed by any joint heretofore made.

I am aware that the faces of fish-plates have 25 been made inclined adjacent to the holes through which bolts are inserted, and hence do not claim such a construction, broadly. My invention consists, simply, in making the 30 plates with their faces immediately around the holes perpendicular to the axes of the holes,

so that they afford an adequate and proper bearing-surface for the nuts, and will obviate springing or bending of the bolts, and in providing the plate with an incline which is within the range of the corners of the nuts.

What I claim as my invention, and desire to 35 secure by Letters Patent, is—

1. The combination, with the abutting rails A, A, of the base-plate B, having an entirely flat upper surface and extending horizontally 40 beyond the bases of the rails, at each side thereof, and fish-plates C, provided with horizontally-extending flanges C', which rest on and are secured by bolts or rivets to the portions of the flat surface of the base-plate beyond the 45 bases of the rails, substantially as herein described.

2. A fish-plate for a railway-rail joint, having 50 its outer side around the holes through which the fish-bolts are to be inserted perpendicular to the axes of the holes, so as to afford a proper bearing for the nuts and obviate the springing or bending of the bolts, and having an incline which will be within the range of the corners of the nuts, substantially as and 55 for the purpose described.

WILLIAM J. STEVENS.
